(57) **CLAIM**

The ornamental design for a bench clamp, as shown and described.

DESCRIPTION

FIG. 1 is an upper perspective view of the bench clamp showing my design in an opened configuration.

FIG. 2 is another upper perspective view thereof, in a closed configuration;

FIG. 3 is a side elevation view thereof;

FIG. 4 is an opposite side elevation view thereof;

FIG. 5 is an end elevation view thereof;

FIG. 6 is an opposite end elevation view thereof;

FIG. 7 is a top plan view thereof; and,

FIG. 8 is a bottom view thereof.

The broken line showing of parts of the drawings is included for the purpose of illustrating use and environment and forms no part of the claimed design.
